(57) CLAIM

The ornamental design for an in-car tape player, as shown and described.

DESCRIPTION

FIG. 1 is a front perspective view from above of an in-car tape player, showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken line showing on FIGS. 1 and 3-7 is for illustrative purposes only and forms no part of the claimed design.
